BUCKET HOLDER

Maurice Lumley, Cincinnati, Ohio, assignor to
 The F. H. Lawson Company, Cincinnati, Ohio,
 a corporation of Ohio

Application October 1, 1940, Serial No. 359,274

2 Claims. (Cl. 224—45)

This invention relates to a bucket holder for carrying two pails or buckets at the same time.

For many cleaning purposes it is desirable to be able to carry two buckets, one of which may contain a soapy water and the other a rinsing water, and while two separate buckets may be used, it is more convenient if the two buckets may be combined to a unit. Devices of this type have been used before but have always been subject to one or more objections. Either special buckets were used which were flattened in the region where they were juxtaposed or an integral structure was provided in which the two buckets were permanently fastened together. In such case, obviously, it is impossible to empty one bucket without emptying the other, and furthermore if it is desired to use only a single bucket, then an empty bucket must be carried along.

With the above considerations in mind, it is an object of my invention to provide a bucket holding device which may be used in connection with ordinary buckets or pails such as may be purchased on the open market. It is another object of my invention to provide a device of the character described in which the buckets do not need to be modified in any way whatever and by means of which the buckets may be attached to or detached from the device at will by a simple operation requiring no tools. It is a further object of my invention to provide a device such as described which will hold two buckets in proper vertical position even though the buckets have tapering walls as is common. Further objects of my invention include the provision of such a device which will be extremely simple and inexpensive to manufacture and which may be used with buckets of a variety of sizes.

These and other objects of my invention which will be clear to one skilled in the art upon reading these specifications or which will be described more in detail hereinafter, I accomplish by that certain construction and arrangement of parts of which I shall now describe an exemplary embodiment. Reference is now made to the drawing forming a part hereof and in which:

Figure 1 is a side elevational view of the device.

Figure 2 is a cross sectional view of the same taken on the line 2—2 of Figure 1.

Figure 3 is a cross sectional view of the same taken on the line 3—3 of Figure 2.

Figure 4 is a perspective view of the device on a reduced scale.

Figure 5 is an assembly view showing the device with one bucket in position and another bucket

being placed in position to show the manner of its use.

Briefly, in the practice of my invention, I provide an element having handle means, said element extending between the two buckets which are to be held therein. At the base of the device I provide at extended positions therefrom means for engaging the bottom rims of the pails and adjacent the top I provide means for engaging 10 over the upper rims of the pails. The means at the bottom end are constructed in a manner to hold the pails in true upright position while the means at the upper end are designed to permit use of the device with buckets or pails of different dimensions.

Referring now more particularly to the drawing, the device consists of a piece of sheet metal or the like indicated generally at 10 and which is preferably flanged as at 11 to provide for stiffness 20 and rigidity. Formed from the material of the member 10 at the top are a pair of ears 12 through which is passed a bail 13 by means of which the device may be carried. Also struck out from the material of the member 10 are the elements 14 and 15. As will be clear from a consideration of Figure 2, the members 15 are struck out and bent slightly inwardly so that they may properly engage the curvature of the buckets. The member 14 being at the point of tangency may be in a plane substantially parallel 30 to the member 10. It will be observed that the members 14 and 15 are of considerable length so that they may accommodate pails or buckets of different dimensions.

At the bottom of the member 10 I provide flanges 16 to which is fixed by spot welding or any desired means a base member 17. The base member 17 is provided with a strengthening rib 18 and the member 10 is notched as at 18a to 40 accommodate the rib 18. The member 17 is of generally hourglass shape as best seen in Figure 3 to accommodate the curvature of the bottom rims of the buckets and it is provided with central upstanding flanges 19 and other upstanding flanges 20. It will be observed that the flanges 19 are somewhat more extended than the flanges 20 and as shown in Figure 5 it is clear that the bottom rim 21 of a bucket is positioned between the flanges 19 and 20. Thus the flange 19 holds the bucket from falling out or sliding out while the flanges 20 maintain the bucket in its vertical position since the flanges 20 are spaced out from the member 10 by an amount dictated by the taper of the bucket.

In use a bucket is positioned as shown in

Figure 5 by bringing the bucket up so that its top rim enters under either the members 15 or the member 14 and the bottom of the bucket is lifted over the flange 19 and seated between the flange 19 and the flanges 20. When thus seated, as shown at the left of Figure 5, it will be clear that the bucket is secured and cannot slip or fall out. Yet when it is desired to change the water or to use a bucket by itself, it is an extremely simple matter to remove it from the holder.

It will be clear that many modifications will suggest themselves to one skilled in the art and I therefore do not intend to limit myself otherwise than as pointed out in the claims which follow. Having now fully described my invention, what I claim as new and desire to secure by Letters Patent is:

1. As an article of manufacture, a bucket holder for use with tapered buckets comprising a piece of sheet metal having a bail fixed to the top thereof, ears struck out in both directions from the top of said member and extending downwardly in planes generally parallel thereto, and

5 a platform at the lower end of said member having interspaced upwardly extending flanges, both of said flanges being spaced further from said member than said ears, and one at least of said flanges on either side being spaced further than said other flanges, said farthest spaced flanges being of less height than said other flanges.

10 2. A device of the character described, comprising a piece of sheet metal having a bail fastened to the top thereof, and having ears struck out and extending downwardly in planes generally parallel to and spaced from said member, and a platform fixed to the bottom of said member at right angles thereto, and having on either side of said member upwardly extending flanges, one flange at least on each side of said member being further spaced from said member than said other flanges, and being of less height, and all of said flanges being farther spaced from said member than said ears.

MAURICE LUMLEY.
